UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

ALLOTTER-CONTROLLING SYSTEM.

Application filed September 21, 1923. Serial No. 663,977.

To all whom it may concern:

Be it known that I, ALBEN E. LUNDELL, a citizen of the United States of America, residing at New York, in the county of Bronx 5 and State of New York, have invented certain new and useful Improvements in Allotter-Controlling Systems, of which the following is a full, clear, concise, and exact description.

10 This application is a continuation in part of the application of Lundell and Clark, Serial No. 301,891, filed June 5, 1919.

This invention relates to a telephone exchange system and more particularly to an 15 allotting system for use in determining the order in which apparatus shall be put into use.

It is an object of this invention to provide an improved allotting system.

20 This invention is especially directed toward the provision of an improved central equipment by means of which a manual operator automatically selects a common equipment to assist her in transmitting calls from 25 an incoming line through automatic switches, to a wanted subscriber.

It is the purpose of this invention to control an allotter by means of a Wheatstone bridge. The Wheatstone bridge when unbalanced associates common equipment with 30 an operator's position to be used for controlling the automatic switches.

A feature of this invention is in the provision of a plurality of common connecting 35 units and a common allotter to control the association of said connecting units to any one of a plurality of operators' positions.

A further feature of this invention is the ability of the Wheatstone bridge allotter to 40 successively allot the connecting units to a plurality of operators initiating simultaneous calls.

These and other features of the invention will be apparent from the following description 45 and accompanying drawing.

While the invention has been disclosed as particularly adapted for telephone systems, it will be apparent, however, from the following description that the invention has a 50 wider utility and by slight modification could be adapted for other control systems.

The accompanying drawing, illustrates a Wheatstone bridge allotter, upper right, a connecting unit and associated sender, and 55 apparatus of an operator's position, lower

left. The operator's position, sender and connecting unit are shown in diagrammatic form only. These parts of the drawing are described in detail in patent application of A. E. Lundell and E. H. Clark, Serial No. 60 654,106, filed July 27, 1923.

The allotter is connected to a plurality of operators' positions and a plurality of connecting units. Each connecting unit has a switch, the same as switch 200. The contacts of all switches, such as switch 200, are multiplied in such manner that certain contacts in each switch are connected to a particular operator's position. In this manner the switch associated with each connecting 70 unit has access to all of the operator's positions.

Description of apparatus.

The allotter relay 301 is of the polarized 75 type actuated from current flowing through its winding in one direction only. The allotter switch and switch 200 are of the well-known step-by-step type controlled by a self-interrupting magnet.

80

Detailed description.

Let it be assumed that the operator wishes to initiate a call in a system requiring that a common sender be associated with the operator's position. To initiate such a call the non-locking start key 101 is actuated. A circuit is thus established to actuate relay 102 which may be traced from grounded battery through the contacts of key 104, winding of relay 102 to ground through the contacts of key 101. Relay 102 in operating establishes a locking circuit for itself through its left contact and armature, resistance 103 to ground. Relay 102 in attracting 90 its right armature establishes a circuit to unbalance the Wheatstone bridge circuit of the allotter. This circuit may be traced from ground through the right armature and contact of relay 102, conductor 238, resistance 331 and over a divided path, one side of which may be traced through resistance 398 to grounded battery and the other side through the winding of polarized relay 301, resistance 330 to grounded battery. Relay 301 is operated in the circuit traced since the direction of current flow is correct for its 95 operation.

Relay 301 in attracting its armature establishes a circuit to operate relay 210. This 100 105 110

circuit may be traced from grounded battery through the left winding of relay 210, switch arm 396 and its associated contact to ground through the armature and contact of relay 301. Relay 210 in operating establishes a locking circuit for itself and an operating circuit for relay 208. The locking circuit may be traced from grounded battery through the right winding, right inner contact and armature of relay 210 to ground through the right inner normal contact and armature of relay 211. The operating circuit for relay 208 may be traced from grounded battery through its winding, right inner contact and armature of relay 210 to ground through the right inner normal contact and armature of relay 211. Relay 210 in operating establishes a circuit to actuate switch magnet 337. This circuit may be traced from grounded battery through the winding and contacts of magnet 337, switch arm 397 and its associated contact to ground through the right outer armature and contact of relay 210. The allotter switch now rotates under the control of magnet 337 to locate an idle connecting unit where it will remain until the allotter Wheatstone bridge is again unbalanced. The ground traced from the right outer contact and armature of relay 210 to the contact associated with switch arm 397 characterizes this allotter switch position as busy to prevent the allotter switch from seizing this connecting unit until it has again become idle.

Relay 208 in attracting its right armature establishes a circuit to balance the Wheatstone bridge. This circuit may be traced from ground through the right contact and armature of relay 208, conductor 399, resistance 332, resistance 330 to grounded battery. The ohmic resistance values of resistances 331 and 332 are the same and the ohmic resistance values of resistance 398 and 330 are the same. Therefore the current flow through both legs of the Wheatstone bridge neutralizes the potential in the windings of polarized relay 301 to cause its release.

The operation of relay 208 further establishes a circuit to rotate switch 200, as hereinafter described, to find the operator's position in which the call is initiated. There are a plurality of operators' positions the same as the one shown in the accompanying drawing. Conductors the same as 105 in each operator's position are connected from the left armature of relays the same as 102 to separate contacts associated with brush 203. Assuming that the relays 102 are normal in all positions except the one in which the call is initiated, ground is connected through the armature of the relays 102 to all of the contacts associated with switch arm 203 except the contact associated with relay 102 in the operator's position initiat-

ing a call. The operation of relay 208 thus establishes a circuit from grounded battery through the winding and contacts of switch magnet 209, left outer contact and armature of relay 208, left normal contact and armature of relay 207, brush 203 and its associated contacts to ground through the armature and contact of the normal relays 102 in other operators' positions. Switch 200 now rotates until brush 203 is associated with the contact connected to the operated relay 102 in the position initiating the call. Ground potential is now supplied to magnet 209 through resistance 103, which is of such value as to prevent the operation of the stepping magnet and to remove the shunt path from the winding of relay 207 to allow the establishment of a circuit through its winding. This circuit may be traced from grounded battery through the winding and contacts of switch magnet 209, left outer contact and armature of relay 208, winding of relay 207 to ground through the left inner contact and armature of relay 208. The current flow in the circuit traced is sufficient to operate relay 207 but on account of the high resistance of relay 207 the current flow is insufficient to actuate switch magnet 209.

The operation of relay 207 establishes a circuit to operate relay 211. This circuit may be traced from ground through the winding of relay 211, contact and armature of relay 207, brush 203 and its associated contact, left armature and contact and the winding of relay 102, contacts of key 104 to grounded battery. The operation of relay 211 establishes a circuit from ground through its right inner armature and contact, resistances 332 and 330 to grounded battery which maintains the balancing ground potential originally supplied at the right armature of relay 208. The operation of relay 211 further establishes a locking circuit for itself which may be traced from ground through its winding and left contact and armature, brush 203, left armature and contact and the winding of relay 102 to grounded battery through the contacts of key 104. The operation of relay 211 further opens the holding circuit for relay 210 and the actuating circuit for relay 208 causing their release. The release of relay 208 opens the actuating circuit for relay 207 causing its release.

It will be noted that the release of relay 210 removes the ground characterizing the allotter switch terminals as busy. Also the release of relay 208 removes the balancing circuit from the upper leg of the Wheatstone bridge. Both of these ground circuits are, however, replaced by ground circuits established through the right inner and outer armatures and contacts of relay 211.

The purpose of the common connecting unit is to associate a common sender with

one of a plurality of operators' positions. At the time the sender is associated with the operator's position, a signal is actuated in the operator's position. The operator may 5 now actuate the apparatus of the sender over conductors 106 to 110 inclusive to control automatic switches.

As soon as the registers of the sender have been set by the operator the release key 104 10 is actuated to release relays 102 and 211. The release of relay 102 opens the unbalancing circuit established through the lower leg of the Wheatstone bridge and the release of relay 211 opens the balancing circuit established for the upper leg of the Wheatstone bridge. Relay 211 is slow to release so that the opening of the unbalancing circuit will precede the opening of the balancing circuit to prevent the possibility of falsely operating 20 the Wheatstone bridge relay 301.

A number of circuits may be established from various operators' positions at one time. Conductors 366 and 367 extend to relays similar to relay 102 located in different operators' positions. With grounds connected to conductors 399 and 238 as previously described throughout the selection of a sender, another ground may be connected to conductor 366 to again unbalance the circuit and operate relay 301. This operates the relay in a second connecting unit in the manner of this disclosure and thus a ground is connected to conductor 365 which will again balance the bridge to neutralize the potential 35 in the windings of relay 301. When the relay in the second connecting units similar to relay 210 has been operated, switch magnet 337 is energized to rotate the switch arms to select another idle connecting unit. The 40 same process of unbalancing and balancing the Wheatstone bridge takes place as other operators require the service of connecting units.

Operators may connect ground simultaneously to conductors 238 and 366 causing the bridge circuit to be unbalanced and relay 301 to operate. A connecting unit is thus associated with one of the operators' positions and the allotter switch is propelled by switch magnet 337 in the manner previously described, to select another connecting unit. However, in this instance, the ground connected to conductor 399 by the first connecting unit does not balance the bridge and relay 301 remains operated. Upon the selection of a second connecting unit, apparatus in that unit is operated to connect a ground to conductor 365, thus balancing the bridge 50 55

to release relay 301. It is apparent that when the two connecting units have been 60 assigned to the two operators, ground is connected to conductors 238 and 366 on one side of the bridge and conductors 399 and 365 on the other side of the bridge. In this manner the bridge is balanced to prepare 65 for a third, fourth, etc., actuation of relays the same as relay 102 to associate connecting units and senders with the various operators' positions.

What is claimed is:

1. In a telephone system, a plurality of switching devices, an allotter to determine the order in which said switching devices are put into use, said allotter including a Wheatstone bridge and numerous side circuits, a relay operable when the bridge is electrically unbalanced and capable of restoration when the bridge is electrically balanced, and means for unbalancing and balancing said Wheatstone bridge by electrical connections to its numerous side circuits. 70 75 80

2. In a telephone system, a plurality of switching devices, an allotter to determine the order in which said switching devices are put into use, said allotter including a Wheatstone bridge and numerous side circuits, and a relay operable when the bridge is electrically unbalanced and capable of restoration when the bridge is electrically balanced, means for unbalancing said Wheatstone bridge when electrical connections are made simultaneously to a plurality of side circuits on one side of said bridge, 85 and means for balancing said Wheatstone bridge when the same number of electrical connections are made to a plurality of side circuits on the opposite side of said bridge. 90 95

3. In an automatic telephone system, in combination, a plurality of operators' positions, a device controlled from said operators' positions for making service connections, an allotter to control the action of parts of said device, said allotter including a Wheatstone bridge and numerous side circuits, and a relay operable when the bridge is electrically unbalanced and capable of restoration when the bridge is electrically balanced, and means for unbalancing and balancing said Wheatstone bridge by electrical connections to its numerous side circuits. 100 105 110

In witness whereof, I hereunto subscribe my name this 19th day of September A. D., 1923.

ALBEN E. LUNDELL.
